CONTAINER

Henry T. Scott, Toledo, Ohio, assignor to The American Paper Bottle Company, Toledo, Ohio, a corporation of Ohio

Application August 22, 1933, Serial No. 686,380

13 Claims. (Cl. 229—37)

This invention relates to paper containers or bottles and particularly to those of the single-service one-piece type such as are used for milk or other liquids.

5 In bottles of this sort such as shown in Patent No. 1,854,319, it has been found difficult if not impossible to make them entirely leak-proof. In practice the bottles are coated with paraffin or similar material before filling are closed after 10 filling, and are then heated at the closure to cause the paraffin to seal the joint. A wire staple or stitching is employed to retain the lapped closure parts against separation.

As heretofore made, the top portions of the 15 bottle where the closure is effected have been so formed that when folded and stitched together they would measure the exact or substantially the exact distance separating the side walls of the bottle except as to the closing rib which stood 20 up vertically from the top portions. As the rib was heated for sealing and held together for stitching, it was necessarily held down close to the plane of the top of the side walls of the bottle, the sealing thus taking place with the rib in that position. Then when the pressure was released, the 25 inherent elasticity of the material of the top portions would cause them to push upwardly and thus separate the connected parts of the rib, thereby breaking the seal and causing the bottle 30 to leak at the closure.

It is an object of the present invention to overcome this defect and to so form the bottle that the seal will remain unbroken and that the top portions and the closure parts will be less easily 35 changed in shape or position in the handling of the bottle after sealing.

It is another object of the invention to so form the top portions of the bottle that in closed position they will be trussed to retain them against 40 relative movement that would cause a breaking of the seal.

It is another object of the invention to so form the top portions of the bottle and so interconnect them that opposite top portions will form truss 45 constructions and that these trusses will support each other to form a particularly strong closed end.

It is another object of the invention to so form the end closure of the bottle or container that 50 the folded-in portions will act as a truss to position the closure to bulge definitely.

It is another object of the invention to so form the end closure of the bottle or container that 55 portions of the closure will definitely space the closing rib outwardly from the container body.

Other objects of the invention will appear from the following description taken in connection with the drawing, which forms a part of this specification and in which:

Figure 1 shows a blank from which the container of this invention may be formed;

Figure 2 shows a completely formed, closed, and sealed container made from such a blank this view being substantially twice the size of the blank in Figure 1;

Figure 3 is a side view of the upper part of the container shown in Figure 2;

Figure 4 is a section on the line 4—4 of Figure 5; and

Figure 5 is a section on the line 5—5 of Figure 15 3.

Referring to the drawing, 1 represents the blank from which the container or bottle is formed. The blank comprises four side walls 2 formed by the score lines 3 upon which the blank 20 is bent into the form of a tube of square or rectangular cross-section. A flap 4 at one end of the blank joins two meeting edges as by gluing.

The bottom of the tube may be closed by two small flaps 5 and two larger flaps 6, these flaps 25 being folded on the score lines 7 and glued to each other to form a three-ply bottom closure.

The top of the side walls is defined by the score lines 8, and above these score lines are the top closure portions of the container. There is a rectangular top portion 9 extending from the upper end of each of two opposite side walls 2. Beyond each of these portions and defined by score lines 10 is a portion 11 for forming a closing rib, and beyond each rib portion 11 and defined by score 35 lines 12 is a fold-over flap 13. The combined extent or width of the two top portions 9 is greater than the distance separating the side walls from which they extend, this distance being determined, of course, by the width of the other two 40 side walls of the container. In the form shown, the container is square in cross-section so that all side walls are of the same width.

By this greater extent or width of the top portions 9, as above described, a truss is formed 45 when these portions are folded on the score lines 8 to bring their free edges (at the score lines 10) together. In other words, these portions 9 form two slanting sides as a peaked roof with gable ends, and no reasonable pressure at the top of 50 the peak can collapse the roof because of the truss thus formed.

Forming a further truss support for the top portions 9 are the two top portions 14 which extend from the tops of the other two side walls 2. 55

The top portions 14 are joined at their ends by score lines 15 to the portions 9. Diagonal score lines 16 for each of the portions 14 permit them to fold inwardly as the portions 9 are folded to effect a closure of the container. These portions 14, or at least their middle zones, are also of greater combined extent or width than the distance separating the side walls to which they are attached, and the diagonal score lines 16 form less than forty-five degree angles, respectively, with the score lines 15 so that when the portions 14 are folded inwardly, their points 17 meet adjacent the center of the base of the rib portion 11, which is some distance above the top of the side walls. Beyond each of the top portions 14 and defined by a score line 18 is a rib portion 19 which folds upon itself at the score line 20 as its portion 14 is folded inwardly as above described. Thus the inner ends 20' of these folded rib portions abut each other between the two rib portions 11, and the larger triangular parts 14' of the top portions 14 and these attached rib portions 19 with their abutting ends 20' form a very substantial truss which assists in supporting the truss formed by the top portions 9 and their rib portions 11. The truss of these portions 14 and 19 is very clearly shown in Figures 4 and 5, the latter figure also showing the truss formed by portions 9 and 11.

In closing the top portions of the container, the portions 14 are folded inwardly toward each other, the portions 9 are at the same time bent toward each other, one of the fold-over flaps 13 is tucked in between the opposite rib portion 11 and the rib portions 19, and then the other flap 13 is folded over the multi-ply rib thus formed by the several rib portions, and while all are held firmly together, a staple 21 is run through them, thus making a permanent closure. Because of the truss form of the closure portions, the rib is definitely positioned somewhat above the top of the side walls of the container, and the stapling machine is thereby enabled to place the staple 21 close to the base of the rib, thus securely holding the closure portions together along that line. As the blank is shown herein, the rib portions 19 are in the form of double oblique parallelograms due to the greater width of the top portions 14 at their middle zones, and the said top portions 14 are of greater combined extent even at their ends than the distance between the sides to which they are attached. Hence, when these top portions are folded, the abutting ends 20' of the rib portions 19 are forced squarely into close contact throughout the extent of said ends 20', and the folded rib portions 19 are pushed up until their tops align themselves with each other and with the tops of the rib portions 11 so that, when one of the fold-over flaps 13 is tucked in, the tops of these rib portions 19 will present an unbroken straight line for sealing at the top of the rib. Thus there is a complete closure of the parts of the rib which the truss arrangement supports and retains.

With this double truss construction and the staple positioned low on the rib there is practically no springing upwardly of the rib closure when the pressure is released after sealing, with the result that the seal effected by the reheated paraffin or other coating as above described is not disturbed or broken and a truly leak-proof container is produced. The truss definitely determines the bulge, definitely spaces the closing rib away from the top of the bottle sides, and prevents harmful readjustment of closure portions after sealing. A single-service one-piece paper

bottle or container with unbroken, and with reasonably unbreakable, seal results from this construction.

Having thus described the invention, what is claimed as new and desired to be secured by Letters Patent is:

1. A self-supporting container for fluid substances comprising a body portion and a folded sealing end closure integral therewith and projecting outwardly from the end of the body, a top portion extending from the upper end of each of two opposite side walls, the combined extent of said top portions being greater than the distance separating the side walls from which they extend, whereby said top portions form a truss when folded to bring their free edges together, and top portions extending from the other side walls and folded to support the first of said top portions in their truss position, said last mentioned top portions underlying the truss formed by the first mentioned top portions.

2. A self-supporting container for fluid substances comprising a body portion and a folded sealing end closure integral therewith and projecting outwardly from the end of the body, a top portion extending from the upper end of each of two opposite side walls, the combined extent of said top portions being greater than the distance separating the side walls from which they extend, whereby said top portions form a truss when folded to bring their free edges together, and top portions extending from the other side walls and integrally connected to the first said top portions and folded to support the latter in their truss position, said last mentioned top portions underlying the truss formed by the first mentioned top portions.

3. A paper container including four side walls, a top portion extending from the upper end of each of two opposite side walls, the combined extent of said top portions being greater than the distance separating the side walls from which they extend, whereby said top portions form a truss when folded to bring their free edges together, and a top portion extending from the upper end of each of the other two side walls, the combined extent of the latter two top portions at their middle zone being greater than the distance separating the side walls from which they extend and said latter two top portions being folded beneath the first mentioned top portions to bring the free ends of their middle zones together to form a truss to support themselves and to add strength to the other top portion truss.

4. A paper container comprising side walls and a closure means, said closure means including a top portion extending from the upper end of each of two opposite side walls and each top portion having a rib portion at its free edge, the combined extent of the top portions being greater than the distance separating the side walls from which they extend, whereby said top portions form a truss when folded to bring their free edges and the rib portions together, and a top portion extending from the upper end of each of the other two side walls and each having a rib portion at its free edge, the combined extent of the latter top portions at their middle zone being greater than the distance separating the side walls from which they extend and said latter two top portions being folded and having their rib portions folded to bring the free ends of said middle zones together and the folded ends of the rib portions together to form a truss to support them-

selves and to add strength to the other top portion truss.

5. A paper container comprising side walls and a closure means, said closure means including a top portion extending from the upper end of each of two opposite side walls and each top portion having a rib portion at its free edge, the combined extent of the top portions being greater than the distance separating the side walls from 10 which they extend, whereby said top portions form a truss when folded to bring their free edges and the rib portions together, and a top portion extending from the upper ends of each of the other two side walls and each having a 15 rib portion at its free edge, the combined extent of the latter top portions at the middle zone being greater than the distance separating the side walls from which they extend and said latter two top portions being folded and having their rib 20 portions folded to bring the free ends of said middle zones together and the folded ends of the rib portions together to form a truss to support themselves and to add strength to the other top portion truss and fold-over flaps and securing 25 means for the rib portions.

6. A paper container comprising side walls and end closure means, said means comprising foldable portions and extensions from the foldable portions forming a multi-ply rib, said foldable 30 portions forming truss supports for themselves and the rib and definitely positioning the rib above the top of the side walls.

7. A paper container comprising side walls and end closure means, said means comprising foldable portions and extensions from the foldable portions forming a multi-ply rib, said foldable 35 portions forming truss supports for themselves and the rib and definitely positioning the rib above the top of the side walls, and holding 40 means for the closure positioned adjacent the base of the rib.

8. A self-supporting paper container for fluid substances comprising a body portion and a folded end closure portion integral therewith and projecting outwardly from the end of the body, the body portion comprising four side wall panels 45 mutually terminating in a plane normal to the container axis, and the end closure portion comprising four extensions, one from each side wall and each being coextensive in width with the side wall to which it is attached, said extensions having their adjacent edges interconnected and each comprising a plurality of angularly disposed panels, two opposed extensions being collapsed 50 and having corresponding similarly shaped inner panels extending from the side walls to which they are respectively attached toward the central longitudinal axis of the container, and being disposed at equal angles of inclination to said axis, each of said collapsed extensions also having two parallel contacting outer panels extending to said axis and being there united by an interconnecting part, and two intermediate panels, each connecting the lower edge of an outer panel to the adjacent outer edge of the associated lower panel, the 55 four outer panels together comprising a central transverse rib with its outer edge disposed in a plane normal to the container axis, with the outer panel interconnecting parts of opposed extensions 60 mutually contacting for a substantial distance along the axis of the container, and the inner panels comprising a truss for supporting said rib extending from the side wall to which it is attached to the base of the said rib and another 65 panel embracing the side of said rib, the rib thus 70

formed and supported being highly resistant to externally applied axial forces.

9. A self-supporting paper container for fluid substances comprising a body portion and a folded end closure portion integral therewith and projecting outwardly from the end of the body, the body portion comprising four side wall panels 5 mutually terminating in a plane normal to the container axis, and the end closure portion comprising four extensions, one from each side wall 10 and each being coextensive in width with the side wall to which it is attached, said extensions having their adjacent edges interconnected and each comprising a plurality of angularly disposed panels, two opposed extensions each comprising 15 an inner panel, two intermediate panels and two outer panels, the outer panels being parallel, mutually contacting and being interconnected by a part extending longitudinally of the container axes, the similar outer panel interconnecting parts of said opposed extensions being in mutual contact for a substantial distance along said axis, the inner panels being similar, extending from the respective container side walls to the axis thereof, and making similar angles 20 with said axis, said inner panels therefore cooperating to form a truss supporting the interconnecting parts of the outer panels, each of the other two extensions having an inner panel 25 extending from the container side wall to which it is attached to the outer panel aforesaid and also having a panel parallel to and engaging two outer panels.

10. A self-supporting paper container for fluid substances comprising a body portion and a folded end closure portion integral therewith and projecting outwardly from the end of the body, the body portion comprising four side wall panels 30 mutually terminating in a plane normal to the container axis, and the end closure portion comprising four extensions, one from each side wall 35 and each being coextensive in width with the side wall to which it is attached, said extensions having their adjacent edges interconnected and each comprising a plurality of angularly disposed panels, two opposed extensions having portions which mutually abut for a substantial distance along the axis of the container and inclined triangular panels, the apices of which 40 meet on the axis of the container and outwardly 45 of the body portion, said panels comprising a truss-like support for said portions, the other two extensions having panels which laterally confine and support the mutually abutting portions of 50 the two first mentioned extensions.

11. A self-supporting container for fluid substances comprising a body portion and a folded sealing end closure integral therewith and projecting outwardly from the end of the body, said 55 end closure embodying folded portions and a rib, the folded portions including triangular panels, the apices of which contact at the axis of the container and outwardly of the body portion, said panels spacing and trussing the rib definitely 60 outwardly from the body.

12. A self-supporting container for fluid substances comprising a body portion and a folded sealing end closure integral therewith and projecting outwardly from the end of the body, said 65 end closure embodying a transversely extending rib and inclined triangular panels having their bases attached to opposite sides of the container respectively and their apices meeting at the container axis directly below the center of the 70 75

rib, the height of each such panel being greater than one-half the base thereof.

13. A self-supporting container for fluid substances comprising a body portion and a folded sealing end closure integral therewith and projecting outwardly from the end of the body, said end closure embodying a transversely extending

rib comprising four trapezoidal panels arranged in pairs, the inner ends of said pairs of panels being united by integral connecting parts, and said parts mutually contacting with each other for a substantial distance along the container axis. 5

HENRY T. SCOTT.
